UNITED STATES PATENT OFFICE

EDWIN MACK MORRIS, OF GALVESTON, TEXAS, ASSIGNOR TO TRIPLE "XXX" COMPANY, A CORPORATION OF TEXAS

DESIGN FOR A FRONT PANEL FOR A THIRST STATION

Application filed December 17, 1929. Serial No. 33,820. Term of patent 7 years.

To all whom it may concern:

Be it known that I, EDWIN MACK MORRIS, a citizen of the United States of America, residing at Galveston, county of Galveston, and State of Texas, have invented a new, original, and ornamental Design for a Front Panel for a Thirst Station, of which the following is a specification, reference being had to the accompanying drawing, forming a part thereof.

In the drawing—

The figure is a front elevation of my design which is thin and flat.

I claim:

The ornamental design for a front panel for a thirst station as shown and described.

EDWIN MACK MORRIS.
